H. RESCH

COMBINED TYPEWRITING AND COMPUTING MACHINE

Filed Feb. 12, 1921

COMBINED TYPEWRITING AND COMPUTING MACHINE.

Application filed February 12, 1921. Serial No. 444,370.

To all whom it may concern:

Be it known that I, HENRY RESCH, a citizen of the United States, residing in Bayonne, in the county of Hudson and State 5 of New Jersey, have invented certain new and useful Improvements in Combined Typewriting and Computing Machines, of which the following is a specification.

This invention relates to combined typewriting and computing machines, and is illustrated in connection with a machine of the Underwood-Hanson type.

It is the usual practice, in completing a computation, to adjust the computing mechanism, as to addition or subtraction, so that upon typing the result or balance and actuating the general operator, the register or totalizer will be cleared. Such machines are provided with clearance or star-keys, which 20 are locked against depression, unless the corresponding totalizers or registers are cleared. When the clearance key is depressed, a star or other clearance sign will be typed on the work-sheet to indicate that 25 the correct result has been typed. Printing of a clearance sign at the beginning of a computation will serve to show that the register is clear at that time. Also, in such machines, provision is usually made of poly- 30 chrome mechanism, whereby the color of the printing may be varied.

In carrying out the invention, provision may be made whereby, instead of printing a star or other clearance sign, the number 35 representing the day of the month will be printed when the clearance key is depressed, and, instead of having a single clearance type and the type-bar controlled by the clearance key, provision may be made of 40 type-blocks or type-heads having thereon types adapted to print the numbers corresponding to the different days of the month, the type-heads and type-bar body to which they are to be attached being so constructed 45 as to permit said type-heads to be readily attached to, or detached from, the type-bar body. Each type-head for attachment to the type-bar body may have both the number indicating the day of the month and the 50 star, the character to be printed being determined by the case-shift mechanism.

It is frequently desirable to print the clearance sign in a different color from that used in printing the numbers connected with

the computation, and this condition is particularly true in case the number of the day of the month is printed as a clearance sign, for otherwise there would be danger of reading the figures representing the day of the month as part of the number printed in connection with the computation. Provision may therefore be made of means whereby, upon actuation of the clearance-sign-printing mechanism, the bichrome mechanism, if set for another color, will be shifted to a 65 position to enable printing of the number of the day of the month in the desired color.

Other features and advantages will hereinafter appear.

In the accompanying drawings, Figure 1 is a fragmentary perspective view, showing my invention applied to so much of a machine of the Underwood-Hanson type as is necessary for the purpose of illustration.

Figure 2 is a perspective view of a detachable type head for use in connection with the mechanism shown in Figure 1.

Figure 3 is a view, showing a type-head such as shown in Figure 2, of a type-bar body.

Figure 4 is a detail view, illustrating the manner in which the link connecting the bichrome mechanism with the lever of the clearance-sign-printing mechanism may be 85 connected with, or detached from, the lever.

In an Underwood-Hanson machine when the register is cleared a star or clearance key 1 may be depressed, but in case the register is not cleared the star-key 1 will be locked against depression. Depression of the star-key 1 will actuate an arm 2 fixed on a shaft 3 to rock the latter and thereby withdraw a latch 4, also fixed to the shaft 3, out of engagement with a pin or projection 5 near the lower end of a link 6 pivoted at 7 near its upper end to an arm 8 fixed on shaft 9. The lower end of the link 6 is normally urged against the shaft 3 by means of a spring 10 connected to the link 6 at its upper end and also to a lug on the arm 8. Upon such shifting of the latch 4 to ineffective position, arm 8 will be swung downwardly by a spring 11, thereby rocking shaft 9, and by means of an arm 12 fixed on said shaft drawing down a link 13 to depress a lever 14 similar to the usual key-levers of the machine. Depression of lever 14 will

wardly to cause a type-head 17 to be swung against the platen 18, printing being effected by means of a ribbon 19.

The clearance-sign-printing mechanism just described may be of the same general character as that disclosed in the patent to Hoyt, No. 1,256,309, granted February 12, 1918.

The ribbon 19 is controlled near the printing point by a ribbon-vibrator 20, which, upon actuation of a typewriter key, is lifted sufficiently to enable printing therethrough by means of type on a corresponding type-bar. As shown herein, the ribbon, which has two color fields extending side by side longitudinally thereof, is adapted to print in black when the upper half or field is positioned at the printing point, and in red when the lower half is so positioned. In order to determine which color field shall be used, the lever 21, which is pivoted at its forward end to the ribbon-vibrator and also at 22 on a fixed part of the frame, is provided above the pivot 22 with pins 23 and 24, the pin 23 being at a greater distance from the pivot than pin 24. Provision is also made of a frame 25 slidable transversely of the machine on the usual universal frame of the escapement mechanism, so as to cause pin 23 to enter a slot at the right thereof or pin 24 to enter a slot at the left thereof. It will be evident that when frame 25 is moved to the rear in the ordinary operation of the escapement mechanism, the ribbon-vibrator will be lifted sufficiently only to bring the black portion of the ribbon into effective position when the pin 23 is in the right-hand slot of the frame 25, but will lift the ribbon-vibrator higher in case the pin 24 is engaged in the left-hand slot. Such action is due to the fact that the pin 23 is a greater distance from the pivot 22 than is the pin 24.

The engagement of the frame 25 with pins 23 and 24 is determined by means of a link 26 connected at one end to frame 25 and at the other end to a frame 27 fixed on a rock-shaft 28. The bichrome mechanism just described is substantially the same as that disclosed in the patent to Cook, No. 926,050, granted June 22, 1909.

Provision may also be made of a signal arm 29 carrying at its upper end two color fields side by side, a black color field 30 and a red color field 31, adapted to be brought into position alternately to be displayed through an opening 32, so as to show at the opening 32 the setting of the bichrome mechanism. In order that the bichrome mechanism may be controlled by the lever 14 of the clearance-printing mechanism, provision may be made of an arm 33 on shaft 28, which may be part of a bell-crank lever

pin 36 to be actuated by a cam 37 pivoted by suitable means, such as a screw 38, on a bracket 39 mounted on a fixed part of the machine. When said cam is in its normal position a dwell portion 40 thereof, substantially concentric with screw 38, will be in engagement with pin 36, which is held thereagainst by means of a spring 41, which may be connected at its lower end to screw 38. The cam 37 is also provided with a lift portion 42 and another dwell portion 43, so that when the cam is swung in clockwise direction the pin 36 will be lifted and the bichrome mechanism shifted, so as to enable printing in red and to cause the red field of the signal to be shown at the opening 32.

The connection between the controlling cam 37 of the bichrome mechanism and the lever 14 may be effected by means of a link 44, pivotally connected at one end with said cam by suitable means, such as a screw 45, and connected at its other end with said lever 14. Preferably, the connection between link 44 and lever 14 is such as to permit ready connection and disconnection therebetween. To this end, link 44 may be provided with lugs 46 and 47, spaced at a sufficient distance apart that lever 14, 95 may be received therebetween, one of the lugs, 47 for example, being provided with a finger 48 to prevent lateral withdrawal of said lever 14 from the slot formed between said lugs 46 and 47.

In order, however, to permit ready connection and disconnection of the link 44 and lever 14, the link is bent near the upper edge of lug 47, so that, when the link 44 is turned to the position shown in Figure 4, 105 the link, by a downward movement, may readily be removed from the lever 14, or, by raising the link to the position shown in Figure 4 and then turning it through ninety degrees about its axis, connection between the link and lever may be effected. When the link has been turned as just stated, it may be attached to the cam 37 by means of the screw 45. Turning of the link will then be prevented, and an operative connection between the link 44 and the lever 14 will be maintained until the link is again detached from the cam 37.

It should be understood that the lift portion 42 and the dwell portion 43 of the cam 37 are so arranged that, when the lever 14 is actuated, the bichrome mechanism will be shifted and the pin 36 will ride on the dwell portion 43 before the clearance type has reached the printing position, thus insuring shifting of the bichrome mechanism at the proper time.

Usually a star is printed to indicate clearance, but, as hereinbefore stated, it may be desirable to print, in place of the star, a

be provided, and, as shown in Figure 2, each of these type-heads may be provided with a star for printing in upper case and a number to indicate the day of the month in lower case, the character to be printed being determined by case-shift mechanism, not shown. In order that the type-heads 49 may be easily attached to or detached from the type-bar 16, each of the type heads 49 is provided with a shank 51 having thereon a headed stud 52, the shank of which may be pressed in an opening 53 at the end of the type-bar 16. The shank 51 of the type-head may also be provided with a slot 54 to receive the shank of a headed stud 55 on type-bar 16, the slot 54 being enlarged by means of a notch 56 in one of its side walls, so as to permit the shank of the stud 55 to be forced into the slot. In pressing the shank of the headed stud 55 into the slot, the walls of the latter are sprung slightly apart so that removal of the shank 51 of the stud 55 from the slot will be resisted. It will be evident that a type-head, when placed on the type-bar 16, will be yieldably held thereon, but may be removed, when desired, to enable substitution of another type-head therefor.

The clearance printing mechanism may be restored to normal position by means of a cam 57 on a carry-over drive-shaft 58, acting on a stud 59 on arm 8, as more fully described in said patent to Hoyt.

It will be evident that by the use of detachable type-blocks having thereon the numbers of the days of the month, it will be a simple matter to determine the day when a clearance sign was printed, and by means of the connection of the clearance-indicating mechanism with the bichrome mechanism the date-number will be printed in a different color than that in which the balance or result is printed, thereby eliminating to a greater extent the danger of reading the date as numbers in the "cents" position of the column.

Variations may be resorted to within the scope of the invention, and portions of the improvements may be used without others.

Having thus described my invention, I claim:

1. In a typewriting machine, in combination, bichrome mechanism normally, in position to cause typing to be effected in one color, a type-bar, and means whereby, upon actuation of said bar, the bichrome mechanism will be shifted to cause printing in the other color.

2. In a typewriting machine, in combination, a special type-head, a polychrome mechanism for determining the color in which matter is to be typed, and means whereby actuation of said special type-head

print in a distinctive color.

3. In a typewriting machine, in combination, a special type-head, a ribbon-vibrator, polychrome mechanism to determine the extent of the vibrations, and consequently the color to be printed, and controlling means for the polychrome mechanism whereby printing by said type-head will always be effected in the same color.

4. In a typewriting machine, in combination, a special type-head, a ribbon-vibrator, polychrome mechanism to determine the extent of the vibrations, and consequently the color to be printed, said polychrome mechanism including a shaft, actuating means for the special type-head, and means whereby said actuating means when operated will rock said shaft, and thereby shift the polychrome mechanism, so as to insure printing by the special type-head in a characteristic color.

5. In a typewriting machine, in combination, bichrome mechanism normally urged to a position to cause printing to be effected in one color, a special type-head, and means whereby actuation of said type-head will control said bichrome mechanism, so as to cause the special type-head to print in the other color.

6. In a typewriting machine, in combination, bichrome mechanism normally urged to a position to cause printing to be effected in one color, a special type-head normally urged to print, means normally restraining said special type-head, means to render said restraining means ineffective, means to restore said type-head to control by said restraining means, and means whereby movement of said special type-head to printing position will insure that the bichrome mechanism will be in position for printing in the other color.

7. In a typewriting machine, in combination, bichrome mechanism normally urged to a position for printing in one color, a special type-head, special type-head-actuating means including a lever, a cam-device adapted to shift the bichrome mechanism to cause printing in the other color, and a link connecting said cam-device to said lever, so that printing by said special type-head will be effected in the other color.

8. In a typewriting machine, in combination, a type-bar constructed so that type-bars bearing type-heads for printing the numbers of the days of the month may be readily attached thereto or removed therefrom, a bichrome mechanism and bichrome mechanism-controlling means whereby printing of the number designating the day of the month by any one of said type-heads will always be effected in the same color.

9. In a typewriting machine, in combination,

- printing will be effected in one color, and bichrome-mechanism-controlling means rendered effective upon actuation of said special type-head, said controlling means comprising an actuating cam having a dwell portion normally positioned at the point where the camming action is to be effected, a lift portion, and a dwell portion to retain the bichrome mechanism in its shifted position.
10. In a typewriting machine, in combination, a special type-head, type-head-actuating means including a lever, bichrome mechanism normally in position to have printing effected in one color, a bichrome-mechanism-shifting cam mounted above said lever, and a link pivoted on said cam and detachably embracing said lever.
15. In a typewriting machine, in combination, bichrome mechanism normally positioned to cause typing to be effected in one color, a type-head, a lever having an operative connection with said type-head, a bichrome-mechanism-shifting cam above the lever, and a link pivoted on said cam and detachably embracing said lever, the lower end of said link being so constructed that, when disconnected from the cam and turned about its axis through substantially a right angle, it may readily be disconnected from the lever by movement in the direction of its axis.
20. In a typewriting machine, in combination, bichrome mechanism normally positioned to cause typing to be effected in one color, a type-head, a lever having an operative connection with said type-head, a bichrome-mechanism-shifting cam above the lever, and a link pivoted on said cam and detachably embracing said lever, the lever being provided with a recess at one side, the shoulders at the end of said recess being spaced to permit the lever to be received therebetween, and one of said shoulders being provided with a lug to retain the lever in said recess, said lug being bent to one side so as to permit entrance of the lever into the recess.
25. In a typewriting machine, in combination, a bichrome mechanism normally urged to a position in which typing may be effected in one color, and bichrome-mechanism-controlling means comprising a shiftable member and a cam having a dwell portion normally adjacent said member, and having a lift portion adapted to actuate said member, and also having a dwell portion to retain said member in actuated position.
30. In a typewriting machine, in combination, a bichrome mechanism normally urged to a position to print in one color, a special type-head, special type-head-actuating means including a lever, and means controlled by said lever whereby said bichrome mechanism will be completely shifted before printing is being effected by said special type-head.
35. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
40. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, a clearance key to render said restraining means ineffective, and means whereby said shifting means may be restored to normal condition.
45. In a typewriting machine, in combination, means, including a special type-bar, for printing the numbers of the days of the month, polychrome mechanism to determine the color of printing, and polychrome-mechanism-controlling means whereby actuation of said type-bar will insure correct positioning of the polychrome mechanism so that such numbers will always be printed in the same color.
50. In a combined typewriting and computing machine, in combination, a clearance key, and means, controlled by said clearance key, for printing the number indicating the day of the month, said printing means comprising one of a complement of type-heads, one type-head being provided for each day of the month, and each type-head having thereon type for printing the number of the day of the month.
55. In a combined typewriting and computing machine, in combination, a clearance key, printing means, whereby actuation of said clearance key will cause the number indicating the day of the month be printed, and polychrome mechanism controlled by said printing means so that such number will always be printed in a characteristic color.
60. In a typewriting machine, in combination, a bichrome mechanism normally urged to a position to print in one color, a special type-head, special type-head-actuating means including a lever, and means controlled by said lever whereby said bichrome mechanism will be completely shifted before printing is being effected by said special type-head.
65. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
70. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
75. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
80. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
85. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
90. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
95. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
100. In a combined typewriting and computing machine, in combination, a bichrome mechanism normally urged to a position to cause printing in one color, means for shifting said bichrome mechanism including an actuating cam comprising a dwell portion normally in effective position, and comprising a lift portion, and also comprising a dwell portion to retain the bichrome mechanism in shifted condition, spring means tending to actuate said cam, restraining means to prevent operation of the cam by said spring means, and a clearance key to render said restraining means ineffective.
105. In a typewriting machine, in combination, means, including a special type-bar, for printing the numbers of the days of the month, polychrome mechanism to determine the color of printing, and polychrome-mechanism-controlling means whereby actuation of said type-bar will insure correct positioning of the polychrome mechanism so that such numbers will always be printed in the same color.
110. In a combined typewriting and computing machine, in combination, a clearance key, and means, controlled by said clearance key, for printing the number indicating the day of the month, said printing means comprising one of a complement of type-heads, one type-head being provided for each day of the month, and each type-head having thereon type for printing the number of the day of the month.
115. In a combined typewriting and computing machine, in combination, a clearance key, printing means, whereby actuation of said clearance key will cause the number indicating the day of the month be printed, and polychrome mechanism controlled by said printing means so that such number will always be printed in a characteristic color.
120. In a typewriting machine, in combination, means, including a special type-bar, for printing the numbers of the days of the month, polychrome mechanism to determine the color of printing, and polychrome-mechanism-controlling means whereby actuation of said type-bar will insure correct positioning of the polychrome mechanism so that such numbers will always be printed in the same color.
125. In a combined typewriting and computing machine, in combination, a clearance key, printing means, whereby actuation of said clearance key will cause the number indicating the day of the month be printed, and polychrome mechanism controlled by said printing means so that such number will always be printed in a characteristic color.
130. In a typewriting machine, in combination, means, including a special type-bar, for printing the numbers of the days of the month, polychrome mechanism to determine the color of printing, and polychrome-mechanism-controlling means whereby actuation of said type-bar will insure correct positioning of the polychrome mechanism so that such numbers will always be printed in the same color.

each day of the month, each type-block being provided with typing means in lower-case position and typing means in upper-case position, the typing means in one case-position printing the number of the day of the month and the typing means in the other case-position printing a clearance sign common to all of the type-blocks.

21. A complement of interchangeable type-blocks for printing clearance signs, said complement comprising a type-block for each day of the month, each block being provided with means to type the clearance sign and also the number of the day of the month when it is to be used.

22. A complement of interchangeable type-blocks for printing clearance signs, said complement comprising a type-block for

20
25
23. The combination with a clearance key, of means, thrown into operation by said key, for printing the number of the day of the month or a star, depending upon the case in which typing is being effected.
